UNITED STATES PATENT OFFICE.

REUBEN M. ROSE, OF BROOKLYN, NEW YORK.

DESIGN FOR A BASE-PLATE FOR PULLEYS.

SPECIFICATION forming part of Design No. 15,216, dated August 5, 1884

Application filed April 2, 1884. Term of patent 14 years.

To all whom it may concern:

Be it known that I, REUBEN M. ROSE, a citizen of the United States, residing in Brooklyn, in the county of Kings and State of New York, have invented and produced a new and original Design for a Base-Plate for Pulleys, of which the following is a specification, reference being had to the accompanying drawing, forming a part thereof.

My design consists in the configuration of the base-plate, which, when viewed in end elevation,

is substantially in the shape of a semi-hexagon, as represented in the drawing.

I claim—

The design for a base-plate for pulleys herein shown and described, the form of the base-plate being substantially that of a semi-hexagon when viewed in end elevation.

REUBEN M. ROSE.
